UNITED STATES PATENT OFFICE.

EMERSON D. SAWYER, OF CHICAGO, ILLINOIS.

YIELDABLE BARRIER.

Application filed August 24, 1925. Serial No. 52,081.

My invention relates to certain novel improvements in yieldable barriers equipped with a pay-out resistance, and has for its principal object the provision of an improved 5 yieldable barrier construction, which will not cause any material damage to the upper part of a vehicle should that vehicle strike the barrier network as it is being lowered into its operative position, across the roadway.

10 The present invention is an improvement over other types of yieldable barriers and eliminates the common objection to barriers, which pay out with a heavy resistance.

A top bus, covered truck or an ordinary automobile, if driven into a yieldable barrier of the existent type when the net of the barrier is being lowered, causes the net to strike against the upper part of the machine and may result in a serious accident to the car and 20 occupants. Yet if that same machine were to strike the barrier net, after it is fully lowered, the only result would be to effectually stop the car by the resistance of the net and its attached brakes.

25 The present invention eliminates the above danger, by making it possible for the upper part of an impinging car to readily tear the net loose at both ends and carry it along with the machine. This arrangement of parts 30 which permits the barrier net to be readily pulled away from its end fastenings prevails in any position, but its fully lowered or operative position.

In this lowered position, the net if hit, 35 brings into play the full pay-out braking resistance.

The practical use of the present invention is also illustrated in the following: In many cases at grade crossings and draw bridges, a 40 car is driven up to the point of danger with the prospect of just getting across the crossing, before the gate closes down and is thus moving at a rather fast pace, when just in front of the safety gate. Possibly they flash 45 under the gate on the oncoming side of the point of danger and get trapped by the gate on the off-going side. Such emergencies require that a car be able to readily crash the gate, in order to save the occupants. If they 50 are facing the barrier net on the oncoming side and the net is due to strike the top of the machine, then tearing the net loose and dragging it on across the crossing is far more preferable than decapitating one or more people. Likewise, if a motorist is facing the off-going gate 55

and is already on the danger spot, his ability to tear the off-going net loose as it is coming down, will readily save him and the machine too.

Thus it is seen that the general object of 60 this invention is to insure emergency safety for the car driver, at a protected crossing and to make yieldable barriers fool proof. Other objects will appear hereinafter.

The invention consists in the combination 65 and arrangements of parts hereinafter described and claimed.

This invention is an improvement over the yieldable barrier devices, disclosed in my previous applications for patents, on yielding or 70 yieldable barriers, a list of which follows: Serial #525,236 filed Dec. 27, 1921, Serial #573,758 filed July 8, 1922, Serial #639,366 filed May 16, 1923, Serial #639,365 filed May 16, 1923, Serial #18,189 (series of 1925) filed 75 March 25, 1925, Serial #18,190 (series of 1925) filed March 25, 1925.

The invention will be best understood by reference to the accompanying drawings, forming a part of this specification, and in 80 which

Fig. 1 is a general perspective view of a yieldable barrier, showing the net first in its upper or inoperative position; second, in an intermediate position such as it passes 85 through when being lowered, and in line with the top of an automobile; and third, in its lowered or operative position, in front of the automobile chassis.

Fig. 2 is a sectional side elevation, through 90 the lower part of one of the columns.

Fig. 3 is a sectional front view on the line A A of Fig. 2.

Fig. 4 is a sectional top view, looking in the direction of B B of Fig. 2.

Fig. 5 is a detailed top view of the connection sockets, shown in Figures 2, 3 and 4.

Fig. 6 is a detailed sectional side view of the connection sockets.

Referring particularly to Fig. 1, 1 and 1^a 100 indicate columns or standards located one on each side of a roadway, 2 indicates a portal connecting the columns 1 and 1^a and 3 indicates a cable net, stretched between the columns 1 and 1^a and operatively movable 105 into positions 3^a and 3^b. The net 3 is lowered into position 3^a when the point of danger which the barrier is protecting is to be closed to traffic. Should an automobile 4 strike the net 3 in its operative position 3^a, the net is 110

run out bringing into play, braking resistance mechanism attached to the net at both ends of 3^a, and within the columns 1 and 1^a.

The net 3 is supported in its approximate 5 horizontal position across the roadway by breakable suspension devices 6, attached to the faces of carriages 5. These carriages 5 can be made to slide vertically simultaneous within the columns 1 and 1^a, and serve as the 10 means to raise or lower the net 3, in a horizontal position.

When the net 3 has momentarily assumed some intermediate position such as 3^b in line with the top of a moving automobile 4 and 15 is struck, the readily breakable suspension devices 6, which are attached to the faces of the carriages 5 are broken, and the net 3 is carried along with the undamaged car 4. It is seen that if the car 4 strikes the net 3 20 when in the position 3^a, the chassis, frame, bumper or radiator of the car 4, impinges on the net and the heavy retarding or braking force exerted by the net merely acts to stop the car. The impact on car 4 in this case is 25 along the line of its greatest weight, or near the center of its mass, thus in this case there can be very little damage to the front of the machine and no injury to the occupants, as the parts in contact with the net at the 3^a position, can withstand such a shock.

Now referring to Fig. 2. This view shows the carriage 5 with the net 3 attached to its face by means of breakable connections 6 and flexible cable connections 7, leading from the net 3 to male connection sockets 8. These male sockets 8 are held lightly in position by let-go supporting devices 9. The carriage 5 is shown equipped with rollers 10, which permit of readily moving carriage 5 vertically 40 in the column 1. Instead of the carriage 5 being directly connected to the flexible operating member 11, the carriage 5, is slidably mounted within a frame 12, which moves vertically in the column 1 carrying the carriage 5 with it, for a purpose hereinafter described.

The male connection sockets 8 are shown locked within female connection sockets 13, which in turn are held lightly in position on 50 the face of drum box 14, by means of let-go supporting devices 15, and fair-leader sockets 16.

The braking apparatus and devices within the drum box 14 consist of reserve cable 55 drums, brake wheel, brake band, tightening devices, brake releasing devices, synchronizing gears and recoiling drum, as disclosed in my previous application for patent.

In the present invention, I prefer to keep 60 the retarding braking devices, or the drum box 14, stationary near the base of the column to serve its purpose only when the net 3 has been fully lowered to an operative position across the roadway, or in such a position that

the sockets 8 and 13 engage one another securely.

Sockets 13 attached to the face of box 14, are secured to the reserve pay-out cables within box 14, and project forward within the carriage 5. It is obvious that the bottom 70 and intermediate horizontal ribs of carriage 5 must be cut away as shown in Fig. 4 to permit of clearance, as the carriage 5 is lowered into an operative position as shown in Fig. 2, with the box 14 just behind it. 75

If the barrier net 3 is struck by car 4, when the net 3 is in an operative or lowered position, as shown in Fig. 2 and as 3^a in Fig. 1, the operation of the several devices is as follows: The cross bar at the end of the net 3 pulling 80 away from carriage 5 breaks the light suspension connections 6, the cables 7 become taut, the male sockets 8 pull outwardly on the female sockets 13, thus putting the attached reserve cables in motion and these in 85 turn function the braking apparatus, as described in my previous application for barrier patents. When the sockets 8 and 13 are made to move outwardly, through the openings in carriage 5, the supporting devices 9 and 15 will automatically unlock themselves 90 from their relative sockets, due to a slotted pull-out connection as shown in Fig. 5 and Fig. 6.

If the net 3 is struck, before the carriage 5 is fully lowered, or in a position indicated by 3^b of Fig. 1, then the male sockets 8 are not yet within the female sockets 13 and no connection is made to the heavy braking resistance within the drum box 14. Thus in 100 striking the net before it is fully lowered, the car 4 is only required to pull out the links 6 and unhook the sockets 8 from their supports 9, which requires a negligible force when applied near the center line of the net. 105

After the net 3 has been hit when in a partially lowered position, as indicated by 3^b of Fig. 1 and torn loose, it is necessary to replace only the net end connections. This operation consists merely of replacing the 110 links 6 and hooking the supports 9 to the sockets 8. If the net 3 has been hit and run out, when in a fully lowered position, then to return the barrier parts to their relatively proper positions, it is necessary to replace the 115 parts the same as above and in addition recoil the reserve cables within the box 14 and hook the supports 15 to the sockets 13. The recoil of the reserve cables may be accomplished mechanically by means of recoil 120 drum, within the box 14 and recoil cable 17, or manually by means of a rewinding crank, both means being disclosed in my former applications for yieldable barrier patents.

Carriage 5 in its movement down the column 1 must be stopped at the proper location, near the base of the column, by means of a bumper 18, so as to insure the proper con- 125

nection between sockets 8 and 13. The flexible operating means 11 is actuated by motor power at some remote part of the barrier and this motive power may be regulated sufficiently correct, so that the member 11 can be stopped accurately at the same spot during each operation of the barrier. In that case the flexible member 11 is attached to the top and bottom of carriage 5 directly.

10 Provision is made though for the possibility of the flexible member 11, not being stopped accurately at the same lower limit during each operation of the barrier. This provision consists of slidably mounting carriage 5 within a frame 12 and attaching a flexible driving member 11 at both the top and bottom of frame 12, at the points 12^a and 12^b. With this latter arrangement, the carriage 5 may be made to stop each time it operates at the same positive spot, by stopper 18, so as to properly engage the sockets 8 and 13, and at the same time permitting frame 12 to coast by to a lower stop limit. The top of frame 12 can move therefore to within a short distance of the top of carriage 5, as at 15^x of Fig. 3. As the frame 12 is raised again by the flexible member 11, it then picks up the carriage 5 at the proper point, as carriage 5 is secured to frame 12 by means of springs 19. These springs are extended on the downward trip of frame 12 and carriage 5. Carriage 5 is held in position on stopper 18, while the frame 12 drifts lower. Lug 12^c is made to engage the lugs 5^a and 5^b during the up and down movements of carriage 5 within frame 12, and also restrict the distance carriage 5 can move within the frame 12.

40 Referring now to Fig. 3. This figure shows a front view of the carriage 5 mounted within the frame 12 and both parts slidably mounted within the column 1.

45 The flexible driving member 11 is attached to the frame 12 at 12^a and 12^b by spring devices 11^a, to eliminate the shock of sudden jerks in overcoming the inertia of carriage 5 and frame 12. Balance cable 17 is also attached to frame 12, at 12^a.

50 Now referring more particularly to Fig. 4. This view shows a horizontal section through the column 1, near its top. The carriage 5 and frame 12 travel along a vertical slot, or pocket in column 1, and are hung in a balance with a counterweight 22, through the medium of cable 17, and a balance sheave 20, located near the top of the column 1. In case the barrier pay-out cables, within box 14, are to be recoiled by hand, then the cable 17 will be dead-ended on the top of counterweight 22. Again in case the reserve cables

60 within box 14 are to be recoiled mechanically, due to the potential energy of the suspended counterweight, then the arrangement of parts is as follows: Cable 17 passing up from the top of frame 12, as shown in Figures 2,

3 and 4, passes over balance sheave 20, at 65 the top of column 1, shown best in Fig. 4; then down and under sheave 21 which is secured to the top of the counterweight 22, then up and over sheave 23, and finally down and into box 14, where the end is coiled on 70 the recoil drum, as more fully disclosed in my previous applications for barrier patents.

A shaft 24 mounted on top of the portal 2, and indicated in Fig. 4 is the means of synchronizing sheaves or sprockets on which 75 the flexible operating means 11 run, near the top of the columns 1 and 1^a, which is also fully disclosed in my former applications for barrier patents.

Fig. 5 is a detailed top view of the two 80 connecting sockets 8 and 13, showing a means consisting primarily of standard cable end sockets, made to conform to a male and female hook-on and let-go arrangement, for the use and purpose disclosed.

85 Fig. 6 is a sectional side view of the same sockets 8 and 13, showing the slanting contact surfaces at 8^a and 13^a to indicate a means of deforming the inner sides of socket 13, and also the bulb end of socket 8, such that the two interlock more efficiently. This mechanical interlocking of these two sockets, is accomplished for the purpose of joining the two sockets together mechanically, so that 90 they will not readily fall apart, as the reserve 95 cables are being run out of the box 14.

It is evident that such a general barrier construction, as I have described above, may be equipped either with or without a sidewalk arm attached. Fig. 1 shows a sidewalk 100 arm 25 attached to the barrier, as is disclosed more fully in my previous applications for barrier patents.

Having described the mechanical parts, which function at one end of the net 3, and 105 within one of the columns, it is understood that the same means are employed at the opposite end of the net, within the opposite column.

By reference to the foregoing description 110 it is apparent that I accomplish many advantages over the constructions of similar devices that are either in use or proposed for commercial purposes, and I also provide an arrangement and construction of parts, 115 which will withstand the usage expected of a device of this character, and add to the possibility of general adaption to public use of yielding barriers by removing the most serious of objections, namely that of injuring the car and its occupants if they attempt to drive the machine, under the lowering barrier net.

120 While I have illustrated and described the preferred form of construction for carrying my invention into effect, this is capable of variation and modification, without departing from the spirit of the invention. I,

therefore, do not wish to be limited to the precise details of construction set forth, but desire to avail myself of such variations and modification as come within the scope of the 5 appended claims.

Having described my invention, what I claim as new and desire to secure by Letters Patent, is:

1. A device comprising a flexible roadway barrier, a standard on each side of the road, a carriage mounted slidably, within each standard, a net stretched between said carriages, means for moving the carriages vertically simultaneously, braking means within the standards, and means for attaching the ends of the net to the braking means, only in the down or operative position.
2. A device comprising a flexible roadway barrier, a standard on each side of the road, a carriage mounted slidably, within each standard, a net stretched between said carriages, means for moving the carriages vertically simultaneously, braking means, means for attaching the ends of the net to the braking means, only in the down or operative position, together with means for obstructing the adjacent sidewalks simultaneously with the obstruction of the roadway.
3. A device comprising a flexible roadway barrier, a standard on each side of the road, a carriage mounted slidably within each standard, a net stretched between said carriages, means for moving the carriages vertically simultaneously, means for balancing the carriages within the shell of the columns, yieldable braking means within the standards, and means for attaching the ends of the net to the yieldable braking means, only in the down or operative position.
4. A device comprising a flexible roadway barrier, a standard on each side of the road, a carriage mounted slidably, within each standard, a net stretched between said carriages, means for moving the carriages vertically simultaneously, means for balancing the carriages, braking means within the standards, said balancing means serving also as means for recoiling the pay-out braking parts, and means for attaching the ends of

the net to the braking means, only in the 50 down or operative position.

5. A device comprising a flexible roadway barrier, a standard on each side of the road, a carriage mounted slidably, within each standard, a net stretched between said carriages, means for moving the carriages vertically simultaneously, means for balancing the carriages, braking means within the standards, the braking means contained within a box near the bases of said standards, 60 said balancing means serving also as a means for recoiling the pay-out braking parts, and means for attaching the ends of the net to the braking means, only in the down or operative position.

6. A device comprising a flexible roadway barrier, a standard on each side of the road, a carriage mounted slidably, within each standard, a net stretched between said carriages, means for moving the carriages vertically simultaneously, means for balancing the carriages, automatically adjustable braking means contained within a box near the bases of said standards, means used for balancing, serving also as means for recoiling 75 the pay-out braking parts, and means for attaching the ends of the net to the braking means, only in the down or operative position.

7. A yieldable barrier comprising a visible 80 roadway net, means for suspending said net across a roadway, and means for placing the net in operative position, said net being capable of severance from the suspending means in positions other than operative.

8. A yieldable barrier comprising a visible roadway net, means for suspending said net across a roadway, means for placing said net in operative position, and means attached to each end of said net when in operative position for retarding and stopping an impinging vehicle, said net being capable of severance from the suspending means in positions other than operative.

In testimony whereof, I have signed my 95 name to this specification.

EMERSON D. SAWYER.
